UNITED STATES PATENT OFFICE.

THOMAS D. HODGE, OF DULUTH, MINNESOTA.

ROLL-COOLING MEANS.

1,339,108.

Specification of Letters Patent.

Patented May 4, 1920.

Application filed September 6, 1918. Serial No. 252,857.

To all whom it may concern:

Be it known that I, THOMAS D. HODGE, a citizen of the United States, residing at Duluth, in the county of St. Louis and State 5 of Minnesota, have invented certain new and useful Improvements in Roll-Cooling Means, of which the following is a specification.

This invention relates to the metal rolling 10 art, and more particularly to means for maintaining the metal working rolls in a relatively cool condition.

One object of the invention is to increase the life of metal working rolls by cooling 15 same in an improved manner.

Another object of my invention is to provide simple and efficient means for cooling metal working rolls in a manner to meet the requirements for successful commercial 20 operation.

These and other objects are accomplished by the arrangement disclosed on the accompanying sheet of drawings, in which—

Figure 1 is a fragmentary front elevation 25 of metal working rolls equipped with my cooling means, and

Fig. 2 is a sectional view of the same taken in the plane of line 2—2 of Fig. 1.

It is a well established fact that unless 30 metal working rolls are maintained reasonably cool, the same wear and abrade rapidly. This is particularly true of rolls which are provided with collars which form passes, the corners of the collars being subjected

35 to extreme temperatures and severe working conditions. It is common practice to supply water in a general way to these rolls for maintaining the same cool, but in spite of this fact, the collars of rolls having passes

40 wear and abrade rapidly. This is due primarily to the fact that these collar portions have not been maintained sufficiently cool. Were water distributed uniformly over the whole length of the rolls, it would be necessary to excessively flood the main portion

45 of the rolls in order to maintain the collar portions at the proper temperature for ideal working conditions, and for reducing to a minimum the wear of said collars. My 50 solution of the problem is to provide a general supply of water to the rolls which is just sufficient for good operating conditions,

and in addition thereto direct a definite supply of water directly to the collars, and particularly to the corners thereof, for 55 maintaining the same in a relatively cool condition.

By referring to the figures of the drawings, it will be noted that I have shown a plurality of associated rolls 10, having 60 passes 11 formed by collars 12 distributed along the length of the rolls. Overlying these rolls is a pipe 13 for conveying water, or any other suitable cooling medium, said pipe being provided along the bottom thereof with a plurality of apertures 14 through which the cooling medium, such as water, may pass and be directed against the rolls 10 throughout the length thereof. As stated above, the collars 12, and particularly the 65 corners thereof are subjected to extreme conditions of temperature and wear. To compensate for these extreme conditions, and for maintaining the collars in a relatively cool condition, I have provided means 70 for directing an additional and a definite supply of water to the collars 12, and particularly the corners 15 thereof. This means for directing the cooling water takes the 75 form of nipples 16, which are connected to the pipe 13, and which are adjustable for directing the flow of water to the corners 15 of the collars 12. I have found that the life 80 of rolls is very materially increased, in fact, as much as 20 per cent., by applying water 85 in this manner.

It is my intention to cover all modifications of my invention falling within the spirit and scope of the following claim.

What I claim is:

In a cooling system for metal working rolls having collars, the combination of means whereby a cooling medium may be supplied along the length of said rolls, and means whereby an additional supply of said 95 cooling medium may be supplied to the collars on said rolls.

Signed at Duluth, Minnesota, this 31st day of August, 1918.

THOMAS D. HODGE.
